W. L. LOESSER,

CAN OPENER.

APPLICATION FILED AUG. 2, 1915. RENEWED AUG. 28, 1916.

1,228,121.

Patented May 29, 1917.

UNITED STATES PATENT OFFICE.

WILLIAM L. LOESSER, OF COMSTOCK, MICHIGAN.

CAN-OPENER.

1,228,121.

Specification of Letters Patent. Patented May 29, 1917.

Application filed August 2, 1915, Serial No. 43,173. Renewed August 28, 1916. Serial No. 117,384.

To all whom it may concern:

Be it known that I, WILLIAM L. LOESSER, a citizen of the United States, residing at Comstock, county of Kalamazoo, State of Michigan, have invented certain new and useful Improvements in Can-Openers, of which the following is a specification.

This invention relates to improvements in can openers.

10 The main object of my invention is to provide an improved can opener which is very efficient and convenient to use and one which can be very economically produced.

Further objects, and objects relating to 15 structural details, will definitely appear from the detailed description to follow.

I accomplish the objects of my invention by the devices and means described in the following specification. The invention is 20 clearly defined and pointed out in the claim.

A structure which is a preferred embodiment of my invention is clearly illustrated in the accompanying drawing forming a 25 part of this specification, in which:

Figure I is a side view of my improved can opener, it being shown associated with the top of a can indicated by dotted lines.

Fig. II is a detail top view of my im- 30 proved can opener, the handle portion being shown in longitudinal section.

Fig. III is a perspective view illustrating the manner of using my improved can 35 opener on a can having a seamed edge.

Fig. IV is a front view further illustrating the manner of using my improved can 40 opener, the can being shown in section.

Fig. V is a front view of my improved can opener still further illustrating the manner in which it may be used, the can being 45 shown in section.

Fig. VI is a front view showing a manner in which my improved can opener may be successfully used on a can having only a 50 small seam.

Fig. VII is a detail end view showing still another manner of using my improved can opener.

In the drawing similar reference numer- 55 als refer to similar parts throughout the several views.

Referring to the drawing, my improved can opener comprises a flat body 1 adapted to receive a handle formed of sections 2 ar- 55 ranged on the sides thereof and secured by rivets 3. The shank portion 4 is preferably

upwardly offset and terminates in a diagonally disposed portion 5 at its front end.

The blade 6 is downwardly offset below the diagonally disposed portion 5 of the shank with the base of the blade joining the shank at the rear of the diagonally disposed portion. The cutting edge 7 of the blade faces upward and is straight and slightly inclined from the longitudinal plane of the body.

Disposed transversely above the blade is a fulcrum jaw 8 having a sharp lower edge 9 provided with a notch 10, the notch being located at the outer side of the blade so that it may be engaged over the cover of a can. The corners 11 of the notch are sharp and are adapted to impinge the top and side of a can. The jaw is turned laterally outward from the front end of the diagonally disposed portion 5 of the shank and is located well toward the front end of the blade, its sharp fulcrum edge being spaced from but quite close to the edge of the blade.

In use the blade is driven through the top of the can and shoved in well to the base of the blade, as indicated by dotted lines in Fig. I. The upward offsetting of the shank permits this and at the same time the hand of the operator does not come into contact with the can.

As can tops vary greatly in the matter of the size of the seam or bead at the edge the notch is made of substantial size to accommodate the largest seams likely to be found. 90 The opener can be tilted to suit the convenience of the operator or held in a horizontal position, and whatever position it is held in the fulcrum jaw is sure to effectively engage either the top and side or the can simultaneously, the side of the can or the top of the can and impinge the same so that there is little likelihood of the can opener slipping, which is of great advantage as accidents in opening cans are ordinarily 100 caused by the slipping of the can opener.

By forming the cutting edge of the blade straight and with but a slight inclination or angle to the horizontal plane of the body of the can opener a relatively long draw cut 105 is secured and the upwardly offsetting of the shank permits the engagement of the blade with the can so that the full cut is readily obtained.

The rear side of the jaw is preferably 110 provided with spaced rests 12, while the shank is provided with a forwardly pro-

jecting spur-like jaw 13 coacting therewith when the can opener is used for removing caps from bottles or the like.

By providing a spaced rest 12 the opener 5 is well adapted for use on bottles having crowned caps or closures as well as those having flat caps.

In Figs. II and IV I illustrate the method 10 of using my improved can opener on a can 13' having a seam or bead 14 of considerable size, the can opener being shown in an outwardly tilted position, such as is effective in manipulating the same to cut in a circle, the outer sharp corner 11 of the fulcrum jaw engaging with the side of the can.

In Fig. V the opener is shown on the same type of can with the fulcrum jaw engaged with the top of the can.

In Fig. VI I illustrate one method of 20 using my improved can opener on a can 15 having a small bead or seam 16, the opener being tilted so that one of the sharp corners 11 of the fulcrum jaw engages the side of the can and the other the top.

In Fig. VII the opener is shown on the same type of can 15 with the fulcrum jaw engaging only the top. This illustrates the great adaptability of my improved can 30 opener which is adapted for use on various types of can, and even the most inexperienced user can use the same with satisfactory results.

My improved can opener is very economical to produce, the body portion, shank, jaw 35 and blade being an integral stamping pref-

erably of uniform thickness. The parts are all in the same plane except the diagonally offset portion 5 of the shank and the laterally disposed fulcrum jaw thereon.

Having thus described my invention, what 40 I claim as new and desire to secure by Letters Patent, is:

A can opener comprising a body portion and an upwardly offset shank portion terminating in a diagonally disposed portion at 45 its front end, an upwardly facing blade downwardly offset from the lower edge of the shank, the edge of the blade being straight and having a slight inclination from the shank, and a fulcrum jaw disposed 50 transversely above the blade and toward its forward end and extending at each side thereof, said jaw being turned laterally from the diagonally disposed end of the shank and having a notch therein positioned 55 at the outside of the plane of the blade and adapted to receive a bead or a corner of a can, the edge of the jaw projecting below the lower edge of the shank and being sharp throughout, there being sharp corners at the 60 edges of the jaw and at the edges of the notch adapted to impinge the side or top of a can.

In witness whereof, I have hereunto set my hand and seal in the presence of two witnesses.

WILLIAM L. LOESSER. [L. s.]
